UNITED STATES PATENT OFFICE.

HENRY S. DAUBENSPECK, OF BUTLER COUNTY, PENNSYLVANIA.

WASHING-MACHINE.

SPECIFICATION forming part of Letters Patent No. 450,721, dated April 21, 1891.

Application filed April 14, 1890. Serial No. 347,927. (No model.)

To all whom it may concern:

Be it known that I, HENRY S. DAUBENSPECK, a citizen of the United States, resident in the county of Butler and State of Pennsylvania, have invented certain new and useful Improvements in Washing-Machines; and I do hereby declare the following to be a full and exact description of the invention, such as will enable others skilled in the art to 5 which it appertains to make and use the same, reference being had to the accompanying drawings, and to figures of reference marked thereon, which form a part of this specification.

15 The invention relates to improvements in washing-machines.

The object of the present invention is to simplify and improve the construction of washing-machines and enable the same to be 20 operated at the expenditure of a small amount of force on the part of the operator and at the same time produce a thorough washing of the clothes.

The invention consists in the construction 25 and novel combination and arrangement of parts hereinafter fully described, illustrated in the accompanying drawings, and pointed out in the claim hereto appended.

In the drawings, Figure 1 is a perspective 30 view of a washing-machine constructed in accordance with this invention. Fig. 2 is a longitudinal sectional view. Fig. 3 is a transverse sectional view. Fig. 4 is a detail sectional view.

35 Referring to the accompanying drawings, 1 designates a semi-cylindrical washing-machine body composed of semicircular sides 2 and a curved bottom 3, and provided with journals 4, extending laterally from the sides 40 2 and mounted in suitable bearings 5 of short uprights or standards 6 of a supporting-frame. The supporting-frame consists of four uprights or standards 6 and 7, connected by horizontal bars 8 and 9, and inclined side 45 bars 10, extending from the upper ends of the short standards 6 to within a short distance of the upper ends of the long standards 7, to which they are secured. Journaled in the upper ends of the long standards 7 is a crank-shaft 11, provided with a

centrally-arranged crank-loop 12, and having at one end a fly-wheel 13 and at the other end a crank-handle 14, by means of which the washing-machine is operated. The crank-shaft is rotated and its motion is communicated to the washing-machine body 1 by a pitman 15, having one end 16 connected to the crank-loop 12 and the other end pivoted in the bifurcated upper end 17 of a central post 18, mounted on the top of the washing-machine body and supported by an inclined brace 19, having enlarged perforated ends 20 secured to the post 18 and the top 21 of the washing-machine body. The end 16 of the pitman is secured to the crank-loop by a section-block and key, and the crank-shaft is prevented moving longitudinally in its bearings by flanges 22, which are arranged on opposite sides of one of the long uprights or standards 7. The inner face of the curved bottom 3 is provided with a series of transverse bars 23, having in their inner edges, which are arranged adjacent the curved bottom, rectangular recesses 24, which form a passage for the water when the washing-machine body is operated, and produce an agitation and force the water through the clothes and enable the same to be thoroughly washed and cleaned.

In the operation of the machine the body 1 is tilted first on one side and then on the other, and the water is caused to rush from end to end of the machine, and passes through the clothes and completely cleans the same. When the washing-machine is not being operated, it is held stationary while the body is being filled with clothes or while the latter are being taken from the body or tub 1 by pins 25, which pass through openings 26 of the inclined side pieces 10 and engage recesses 27 of cleats 28, secured to the sides 2 of the body near one end thereof.

From the foregoing description and the accompanying drawings the construction, operation, and advantages of the invention will 95 be readily understood.

What I claim is—

In a washing machine, the combination of the frame comprising the short standards 6, the long standards 7, and the bars connect- 100

ing the standards, the body mounted in the frame and journaled in suitable bearings of the short standards, the central post 18 rising from the top of the body and having its upper end bifurcated, the inclined brace 19, secured to the top of the body and the post, the crank-shaft, and the pitman having one end con-

nected to the crank-shaft and the other end pivoted in the bifurcated upper end of the central post, substantially as described.

HENRY S. DAUBENSPECK.
